UNITED STATES PATENT OFFICE.

SAMUEL FRANK, OF PHILADELPHIA, PENNSYLVANIA.

DESIGN FOR A HOLDER FOR GREEN CORN.

SPECIFICATION forming part of **Design No. 27,035**, dated **May 11, 1897**.

Application filed February 8, 1897. Serial No. 622,548. Term of patent 3¹ years.

To all whom it may concern:

Be it known that I, SAMUEL FRANK, a citizen of the United States, residing in the city and county of Philadelphia, State of Pennsylvania, have invented and produced a new and original Design for Holders for Green Corn, of which the following is a specification, reference being had to the accompanying drawing, forming part thereof.

10 The leading feature of my design for a holder for green corn is handled jaws with teeth thereon.

A designates jaws which bulge outwardly

at B and are connected with the handles C, as at D. On the ends of the jaws are inturned 15 teeth E, which are opposite to each other and occupy positions in front of the chamber F, formed by said jaws.

What I claim is—

The design for a holder for green corn substantially as described and shown.

SAMUEL FRANK.
